UNITED STATES PATENT OFFICE

2,508,361

FEEDING MECHANISM FOR SOLE ROUNDING MACHINES

Corwin W. Baker, Beverly, Mass., assignor to United Shoe Machinery Corporation, Flemington, N. J., a corporation of New Jersey

Original application December 29, 1945, Serial No. 638,285. Divided and this application August 6, 1948, Serial No. 42,908

10 Claims. (Cl. 12—85)

1

This invention relates to machines for rounding soles of shoes to the desired peripheral contour and, more particularly, is concerned with the rough rounding of shoes of the stitchdown type in which the upper material is flanged outwardly from the side of the shoe, and is stitched to the margin of the outsole.

The usual type of machine for performing this operation has a guide for positioning the shoe with respect to a rounding knife or other trimming member, the guide being arranged to engage the outwardly flanged upper material and to be seated in the crease between the shoe upper and the sole edge. It is evident that any irregularities in the flanged upper material are likely to impede the advance of the shoe past the guide as well as to affect the positioning action of the guide upon the shoe.

In my copending application for United States Letters Patent Serial No. 638,285, filed December 29, 1945, there is disclosed a machine of the above type having a rotatable pressure member arranged to impart a smoothing action upon the flanged upper material just before it is engaged by the guide so as to eliminate any projection which otherwise might interfere with the feeding movement of the shoe, or disturb its position with respect to the rounding knife. Hence steady and regular feeding of the work is assured, so far as the action of the above-mentioned guide upon it is concerned.

This object is furthered in the same machine by the provision of improved feeding means which is claimed in this application, a division of my above-mentioned application.

An object of the present invention is to so engage the work by opposite movable feed members that none of their advancing action will be lost, and the sole, if yieldable, will not be deformed. To this end, one of the two members is caused to move more rapidly than the other in the direction of work-advance, and, by making the work-engaging surfaces converge, there is caused a wedging effect upon the work, so it will be firmly grasped during its feed. Moreover, with a feed member engaging the upper margin of the shoe-bottom and a rest engaging a tread-surface, the movement of the rest is made rectilinear rather than with a component acting toward the bottom-edge, so there is avoided the tendency to force yieldable sole-material outwardly where it would be positioned improperly for trimming. The bottom-rest may have a convexly curved work-engaging surface, it being preferably in the form of an outwardly curved strip pivoted at one

2

end upon a slide and with the other end forced yieldably toward the companion feeding member. It is shown as adjustable as to the vertical angle of its work-engaging surface, its pivotal connection being to a carrier which is variable in position upon the slide.

A further object of the invention is to decrease the length of time in a work-feeding cycle in which the advance is delayed or interfered with.

10 With opposed members movable in directions in which they first feed the work a step and then return to their initial positions for another step, the time during which the work is being grasped, in preparation for advance, is customarily taken from this advance, and the interval during which the work is released at the termination of a feeding step delays the time of return movement, particularly since the separation must be sufficient to avoid rearward displacement of the freed work.

15 I have materially reduced these periods ineffective for work-advance, by the inclusion, in the means by which the feed members are carried relatively toward and from each other, of two members which are movable simultaneously in opposite directions for the production of an accelerated relative movement. In the present instance, these members are provided with cooperating cam-portions which are engaged and disengaged by the opposite movement, thereby alternately causing the feed members to approach rapidly and then permitting them similarly to separate.

20

In the accompanying drawings illustrating one of the several possible embodiments of the invention:

35 Fig. 1 shows the more essential portions of my improved rounding machine in front elevation; Fig. 2 is a side elevation, looking from the left in Fig. 1;

40 Fig. 3, an elevation of the opposite side of the machine;

45 Fig. 4, a perspective view of the elements more closely associated with the work;

Fig. 5, a broken top-plan-view of the bottom-rest and the cooperating feed-arm;

Fig. 6, a detail, in elevation, of the mounting for the bottom rest, viewed from the right of the machine; and

Figs. 7, 8, 9 and 10 are, respectively, enlarged sections on the lines VII—VII, VIII—VIII, IX—IX and X—X, Fig. 7 showing the means for oscillating the feed-arm, Figs. 8 and 9, the means for producing the work-engaging movement of the feed-arm, and Fig. 10, the means for reciprocating the bottom-rest.

A considerable number of the elements of the present machine are substantially the same as in the well-known Goodyear Universal Rounding and Channeling Machine, Model E as disclosed in Letters Patent of the United States No. 1,039,606, granted June 25, 1912, upon an application filed in the name of Frederick H. Perry. Referring first to parts of the present machine which may readily be identified in the Perry patent, a vertical column 20 carries at its upper extremity a head 22 upon which the various work-engaging and operating members are supported. A crease-guide 24 of generally U-form, to receive the crease of a shoe being operated on, is adjustably secured to the upper forward portion of the head by slot-and-screw connections 26, instead of being arranged for vertical oscillation, as in the previously mentioned machine. In the upper portion of the head 22 is journaled a horizontal shaft 28, oscillated as will be later described, and having fixed to its forward extremity a feed-arm 30 lying between the opposite arms of the crease-guide. With the crease of a shoe applied to the crease-guide, as appears in Fig. 4, the usual feed-point fixed to the feed-arm receives contact of the flange of a stitchdown-shoe or the welt applied thereto. Reciprocable in horizontal ways at 32 in the head is a slide 34, in which is fixed a rounding knife 36 cutting against an anvil set in the feed-point. The construction of the knife-operating means is the same in the present machine as in the above-mentioned Perry machine.

Now, to describe the novel features of this invention and the changes which have been made in the original machine to adapt it to its present use, it may first be said that the mechanisms more directly connected with the channeling of the shoe and for varying the extension of its rounded edge are omitted. Projecting from the lower portion of the head at the front is a stationary sleeve 38, upon the forward end of which is a vertical extension 40 having in its front face a horizontal guideway 42 (Fig. 5). In the guideway a slide 44 is movable, it being reciprocated through a forwardly projecting stud 46 lying in a slot 48 formed longitudinally of an arm 50 fast upon a shaft 52 arranged to oscillate in the sleeve 38 and in a bearing in the head 22. The shaft is oscillated by an arm 54 fast upon it (Fig. 10), a toggle 56, pivoted to the arm and to the head, and an eccentric-rod 58 joined to the center of the toggle, the strap of which rod surrounds an eccentric 60 secured to a shaft 62 journaled in the head parallel to the shaft 52. The shaft 62 carries a pulley 64 through which it is rotated from some source of power.

A rearwardly offset portion at 66 of the slide 44 has, at its front, a vertically curved surface 68 (Fig. 6) against which rests the complementary surface 70 of a carrier member 72 adjustably secured to the slide by a slot-and-screw connection 74. Joined to the carrier by a vertical pivot-screw 76 is an outwardly curved horizontal strip 78, the central portion of which lies opposite the feed-arm 30, furnishing a rest for the bottom or tread-surface of a sole attached to a shoe. The end of the rest 78 opposite its pivot has fixed in it an eye 80 engaged by a hook 82 providing a universal connection to a horizontal rod 84 passing through an opening in a rearwardly extending bracket 86 attached to the slide 44. Interposed between the angular rear extremity of the bracket and a collar 88 secured to the rod by a screw 90 is a helical spring 92. The rest 78 is urged by the spring toward the feed-arm, to an extent per-

mitted by a collar 94 secured to the rod for engagement with the end of the bracket, to hold the margin of the shoe-bottom gripped yieldably between the opposed members. The applied force 5 may be altered by changing the position of the collar 88 upon the rod. The bottom-rest may be withdrawn from the feed-arm by an arm 96 forked at its upper end to receive the rod 84 and attached to a spindle 98 (Fig. 2) guided to move 10 horizontally in the head 22. Fixed to the spindle is a collar 100, with which contacts an arm 102 rising from a shaft 104 journaled in the head transversely of the spindle. To the end of the shaft 104 opposite the arm 102 is fixed an arm 106 (Fig. 3), the upper end of which is engaged by the depending arm of a bell-crank-lever 108 fulcrumed upon the head. To a horizontal arm of the bell-crank is pivoted a rod 110 leading to an unillustrated treadle, which is held raised by the 20 customary spring. The normal position of the bell-crank is determined by a stop-screw 112 contacting with the head. Depression of the treadle and rod 110, acting through the chain of elements just indicated, shifts the arm 96 rearwardly against a collar 114 fast upon the rod 84. This draws the bottom-rest rearwardly from the feed-arm, compressing the spring 92. The feed-arm 30 is oscillated in the correct time relation to the reciprocation of the bottom-rest to advance a shoe during an operation upon it, through an arm 116 having its hub secured to the shaft 62 (Fig. 7), a toggle 118, pivoted to the arm and to the head 22, and an eccentric-rod 120 actuated by an eccentric 122 fast upon the shaft 62.

During the oscillation of the feed-arm 30 and the reciprocation of the bottom-rest 78, they are separated at the end of the forward stroke, freeing the work after a step in its advance, then closing again upon the work at the termination 25 of their idle reverse movement in preparation for the production of the succeeding step. For this purpose, a movement of reciprocation fore and aft of the machine is imparted to the feed-arm. This arm is urged yieldably away from the bottom-rest by an expansion-spring 124 (Fig. 2) contained in an axial bore in the shaft 62 and abutting at its outer end against a plate 126 attached to the head 22. Arranged to turn loosely upon the shaft 28 are arms 128 and 132. The arm 128 (Fig. 9) is oscillated by its connection to an eccentric-rod 134, the strap of which encircles an eccentric 136 fast upon the shaft 62. The arm 132 (Fig. 8) is oscillated oppositely to the arm 128 through an eccentric-rod 138 actuated by an eccentric 140 upon the shaft 62. On the inner face of the hub of the arm 128 is a cam-depression 142, and cooperating with this, upon the hub of the arm 132, is a cam-projection 144. At the time the feed-arm 30 is to be carried into to clamp the work against the back-rest 78, the cam-depression 142 is turning counterclockwise, as viewed from the front of the machine, while the cam-projection 144 is turning clockwise. As the inclined end walls of the depression and projection engage and pass each other, as a result 30 of their opposite movement, since the hub of the arm 128 bears at its outer side against the adjacent surface of the head 22, the projection 144 rides out of the depression 142 onto the end 35 of the hub of the arm 130. The arm 116 is fixed to the shaft 28 and is backed by a collar 146, also fast upon the shaft and spaced from the adjacent surface of the head. The feed-arm 30 is therefore abruptly shifted rearwardly toward the bottom-rest 78 to grip the sole-margin, which is

thereafter as quickly freed when the projection and depression again mesh, because of the reverse oscillation of the arms 130 and 132 and the expansion of the spring 124. By the prompt engagement of the feeding members, there is utilized the maximum time in an operating cycle of the machine during which the work may be advanced, and by their prompt disengagement, there is minimized the time during which the work might back-feed.

To outline the manner in which the feed-arm 30 and the bottom-rest 78 cooperate to advance the work for the rounding of the sole *s* of a shoe *S* by the chopping knife 36, the operator, by drawing down the rod 110 through the treadle, retracts the bottom-rest from the feed-arm and inserts the sole-margin between them, then releasing the treadle. Engagement of the crease with the guide 24 (Fig. 4) determines the path through which the work will move and the width of the sole-extension produced by successive cuts which the knife makes against its anvil. At the beginning of a work-advancing cycle, and viewing the elements from the operator's position at the front of the machine, both the feed-arm and the bottom-rest are at the extreme right, with the bottom-rest having moved farther in that direction than the feed-arm. They are spaced from each other transversely to such an extent that a sole which has been between them will have been released. First, the feed-arm is carried rapidly in by the cams 142 and 144, so it acts upon the upper margin of the shoe-bottom to clamp the tread-surface against the bottom-rest. Starting at substantially the same time, the two feeding members are moved to the left through their full strokes by the respective eccentrics 60 and 122, the bottom-rest traveling more rapidly than the feed-arm. As a result of this different rate of movement, and the fact that, as may be seen in Fig. 5 of the drawings, the work-engaging surfaces of the members converge in the direction of travel, a wedging action is produced, the bottom-rest forcing the sole-margin outwardly against the feed-arm. Thus, without the danger of marring the tread-surface of the sole, which would exist with the use of a roughened member, the work is firmly gripped, even if the sole presents a polished or smooth surface. Having made the forward and fully effective feed-step, the feed-arm is quickly withdrawn by the spring 124 as permitted by cams 142 and 144 to release the work, and the bottom-rest 78 is retracted to its initial position by the eccentric 60, the feed-arm remaining in its advanced position while the rounding knife 36 comes forward and makes its cut against the anvil on the feed-point. This is followed by retraction of the feed-arm under the influence of the eccentric 122 so both members are restored to normal, ready for the succeeding operating cycle. It is to be noted that the work-feeding movement of the bottom-rest 78 is rectilinear and not oscillatory, as in the old machine. If the bottom-rest were to swing upwardly as well as forwardly in the advance of the work having soles of rubber or other readily compressible material, its upward pressure would cause the sole-edge to bulge outwardly and to be held in this condition while the rounding knife makes its cut. When released, the edge would spring back so an objectionable inward bevel would be formed instead of the desired vertical edge.

In the rounding of stitchdown shoes, in which a flange *f* of the upper material extends over the

upper margin of the soles *s* (Fig. 4), irregularities occur in the surface of the flange which contacts with the crease-guide 24. These may be the result of cutting away or pinking the flange to facilitate carrying the upper about the more sharply curved peripheral portions of the shoe at the crease *c*, or, in absence of such pinking, the flange may be puckered or gathered at the curved portions. In the first instance, as the work is fed forward, the spaced fingers of the flange produced by the pinking may engage or be deflected outwardly by the edge of the guide. This will so position them that they will not be trimmed by the knife 36. The projections of the unpinked flange, by striking against the edge of the crease-guide, tend to interfere with the advance of the work. To guard against these difficulties, I attach to the top of the head 22, at the front, a bracket 160 through which is a horizontal bore. Secured in the bore by a set-screw 162 is the shank 164 of a block 166. In a bore in the block, extending transversely of the shank 164 is the shank 168 of a bearing member 170 fixed in position by a set-screw 172. Rotatable in the bearing member is a spindle 174, the location of which longitudinally of its axis may be determined by collars 176, 176 adjustably secured to the spindle by set-screws 178. The lower collar is normally spaced from the adjacent end of the bearing. The lower extremity of the spindle is roughened, it being herein shown as toothed by forming in its conical end 179 peripheral grooves 180 and longitudinal grooves 182. The capacity for variation in the position of the shanks 164 and 168 both longitudinally and angularly, and for change in the longitudinal position of the spindle, renders the end of said spindle universally adjustable, so it may be located in any chosen relation to the edge of the guide 24 toward which the upper margin of the shoe-bottom advances. This is preferably with the conical end in close proximity to the guide, the axis of the spindle being upwardly and rearwardly inclined and the apex of the end preferably lying at or just below the crease-entering end of the guide 24 and the side which engages the upper-flange *f* situated approximately in the plane of the flange-contacting face of the guide. The spindle 174 is rotated in a contraclockwise direction, as viewed from above, by a pulley 184 fast upon it, and driven by a belt 186 operating over the guide-pulleys 188 rotatable upon a bracket 190 secured to the top of the head 22, and over a pulley 192 fixed to the shaft 62.

As the surface of the flange *f* of the shoe *S* approaches the conical spindle-end 179, it enters a converging throat formed between the upper-margin of the sole *s* and the curved surface of the spindle. The roughened surface of the spindle presses against the surface of the flange and smooths out any divided portions, unfailingly insuring that they will pass at the inner side of the guide 24 and will not contact with its edge. Uneven portions of the flange-surface are compressed and smoothed by the combined pressure and rotation of the spindle, so they lie at the inner side of the guide, where they do not interfere with the feed of the work by engagement with the guide-edge. Because of the direction of rotation of the spindle-end, it offers no frictional resistance to the advance of the work. Since the spindle is capable of rising to a limited extent in its bearing, it floats in the crease *c* and is displaceable upwardly as the work is turned at curved portions. Consequently, it does not affect the po-

positioning of the shoe by the guide. The angular adjustment of the bottom-rest 78 through change in the position of its carrier 72, disposes the tread-engaging surface correctly for differently curved shoe-bottoms. Since the center of curvature of the surfaces 68 and 70 preferably lies at the upper edge of the rest, the adjustment does not disturb the desired vertical relation of said rest to the cooperating portions of the crease-guide 24 and feed-arm 30.

Having thus described my invention, what I claim as new and desire to secure by Letters Patent of the United States is:

1. In a rounding machine, trimming means constructed and arranged to make a succession of trimming strokes through the margin of a shoe-sole, opposite members movable in alternation with said trimming means to advance the work between successive trimming strokes to receive the action of the trimming means, and means for moving one of the members in the direction of advance more rapidly than the other member.

2. In a rounding machine, trimming means constructed and arranged to make a succession of trimming cuts through the margin of a shoe-sole, opposite members movable after each cut to advance the work to receive the succeeding cut from said trimming means, the work-engaging surfaces of the members converging in the direction of advance, and means for moving one of the members in the direction of advance more rapidly than the other, thereby wedging the work between the converging surfaces.

3. In a sole-rounding machine, a movable feed member for engagement with the upper margin of a shoe-bottom, a rounding knife cooperating with the feed member to trim the shoe-sole, a movable rest for engagement with the tread-surface of the sole, and means for moving the rest in a rectilinear path in cooperation with the feed member to advance the work to receive the action of the rounding knife.

4. In a sole-rounding machine, a movable feed member for engagement with the upper margin of a shoe-bottom, a rounding knife cooperating with the feed member to trim the shoe-sole, a movable rest for engagement with the tread-surface of the sole, the work-engaging surface being curved convexly toward the feed member, and means for moving the rest in a rectilinear path in cooperation with the feed member to advance the work to receive the action of the rounding knife.

5. In a rounding machine, a movable feed member for engagement with the upper margin of a shoe-bottom, a rounding knife cooperating with the feed member to trim the shoe-sole, a movable rest for engagement with the tread-surface of the sole, and means for moving the rest in a rectilinear path in cooperation with the feed member and more rapidly than said feed member to advance the work to receive the action of the rounding knife.

6. In a rounding machine, a movable feed member for engagement with the upper margin of a shoe-bottom, a rounding knife cooperating with the feed member to trim the shoe-sole, a guide member provided with ways, a slide movable in the ways, an outwardly curved strip piv-

oted to the slide and furnishing opposite the feed member a rest for the tread-surface of the sole, means for forcing the strip yieldably toward the feed member, and means for reciprocating the slide to cause the strip to act with the feed member and advance the work to receive the action of the knife.

7. In a rounding machine, a movable feed member for engagement with the upper margin 10 of a shoe-bottom, a rounding knife cooperating with the feed member to trim the shoe-sole, a guide member provided with ways, a slide movable in the ways, a carrier variable in position upon the slide, an outwardly curved member pivoted upon the carrier and furnishing opposite the feed member a rest for the tread-surface of the sole, and means for reciprocating the slide 15 to cause the rest to act with the feed member and advance the work to receive the action of 20 the knife.

8. In a rounding machine, a movable feed member for engagement with the upper margin 25 of a shoe-bottom, a rounding knife cooperating with the feed member to trim the shoe-sole, a guide member provided with ways, a slide movable in the ways, a carrier variable in position 30 upon the slide, a strip pivoted to the carrier and furnishing opposite the feed member a rest for the tread-surface of the sole, the slide and carrier 35 having complementary contacting surfaces curved about a center lying substantially at the upper edge of the strip and permitting the carrier to be moved upon the slide, and means for securing the carrier in different positions resulting from such movement.

9. In a rounding machine, a trimming member, members arranged for engagement with opposite sides of a shoe-bottom, means for advancing and retracting the members to produce successive feeding steps presenting the work to the trimming member, and means for moving the two feeding members relatively toward and from each other alternately to grasp and release the work, said moving means having two members 45 movable simultaneously in opposite directions for the production of relative movement of the feeding members.

10. In a rounding machine, a rounding knife, a feed-arm and a rest for engagement with the 50 opposite sides of a shoe-bottom, means for advancing and retracting the arm and rest to produce successive feeding steps presenting the work to the rounding knife, two rotatable members having cooperating cam-portions, means for 55 turning the members in opposite directions to cause the engagement and disengagement of the cam-portions and thereby alternately cause the separation and permit the approach of the two members, and means for communicating such movements of the members to the feed-arm.
